(Cl. D61—1)

To all whom it may concern:

Be it known that we, Ray C. Wilcox and Bruce H. Dalton, citizens of the United States of America, residing at Culver City, in the county of Los Angeles, State of California, and Los Angeles, in the county of Los Angeles, State of California, respectively, have invented a new, original, and ornamental Design for a Pedestal for Cameras, of which the following is a specification, reference being had to the accompanying drawing, forming a part thereof.

Figure 1 is a front perspective view of a camera pedestal showing our new design, the pedestal being shown in retracted position;

Figure 2 is a side perspective view of the device of Figure 1 with the pedestal in extended position; and

Figure 3 is a top plan view of the device as in Figure 1.

The essential features of our design are shown in full lines.

We claim:

The ornamental design for a pedestal for cameras, as shown and described.

RAY C. WILCOX.
BRUCE H. DALTON.
